United States Patent Office

Des. 182,081
Patented Feb. 11, 1958

182,081

DUTCH OVEN OR SIMILAR ARTICLE

David L. Painter, Evanston, Ill., assignor to West Bend
Aluminum Co., West Bend, Wis., a corporation of Wisconsin

Application April 8, 1957, Serial No. 45,625

Term of patent 14 years

(Cl. D44—1)

Fig. 1 is a view in side elevation of a Dutch oven or similar article embodying my new design;

Fig. 2 is a top plan view thereof;

Fig. 3 is a cross-sectional view taken on the line 3—3 of Fig. 2; and

Fig. 4 is a cross-sectional view taken on the line 4—4 of Fig. 1.

I claim:

The ornamental design for a Dutch oven or similar article, substantially as shown.
